UNITED STATES PATENT OFFICE

118,702

DESIGN FOR A SERVICE STATION

Theodore H. Joseph, Mamaroneck, N. Y.

Application June 1, 1939, Serial No. 85,279

Term of patent 3½ years

To all whom it may concern:

Be it known that I, Theodore H. Joseph, a citizen of the United States, residing at Mamaroneck, county of Westchester, State of New York, have invented a new, original, and ornamental Design for a Service Station, of which the following is a specification, reference being had to the accompanying drawing, forming a part thereof.

Figure 1 is an elevation in perspective of a service station, showing my new design wherein

the rear and left side portions of the tower are plain surfaced; and Figure 2 is a top plan view thereof.

The essential features of my design reside in the tower shown in full lines.

I claim:

The ornamental design for a service station, substantially as shown and described.

THEODORE H. JOSEPH.
